US00D731640S

(12) **United States Design Patent**
Kim et al.

(10) **Patent No.:** US D731,640 S
(45) **Date of Patent:** ** Jun. 9, 2015

(54) **RESERVOIR FOR A WATER FLOSSER**(71) Applicant: **WATER PIK, INC.**, Fort Collins, CO (US)1,650,686 A 11/1927 Binks
1,669,889 A 5/1928 Andrews et al.
1,681,320 A 8/1928 Bergl et al.

(Continued)

(72) Inventors: **Hyunchul Kim**, Chicago, IL (US); **Taiwon Choi**, Glenview, IL (US)

FOREIGN PATENT DOCUMENTS

(73) Assignee: **WATER PIK, INC.**, Fort Collins, CO (US)CA 851479 9/1970
CH 502817 A 2/1971

(Continued)

(**) Term: **14 Years**(21) Appl. No.: **29/466,916**(22) Filed: **Sep. 12, 2013**

OTHER PUBLICATIONS

US RE27,274 01/1972, Mattingly (withdrawn).

U.S. PATENT DOCUMENTS

555,588 A 3/1896 Spencer
1,278,225 A 9/1918 Schamberg
1,464,419 A 8/1923 Gill
1,498,267 A 6/1924 Hachman

FIG. 1 is a front, right isometric view of a reservoir for water flosser;

FIG. 2 is a front, left isometric view of the reservoir for water flosser of FIG. 1;

FIG. 3 is a right-side elevation view of the reservoir for water flosser of FIG. 1.

FIG. 4 is a left-side elevation view of the reservoir for water flosser of FIG. 1.

FIG. 5 is a front elevation view of the reservoir for water flosser of FIG. 1.

FIG. 6 is a rear elevation view of the reservoir for water flosser of FIG. 1.

FIG. 7 is a top plan view of the reservoir for water flosser of FIG. 1; and,

FIG. 8 is a bottom plan view of the reservoir for water flosser of FIG. 1.
